UNITED STATES PATENT OFFICE.

ERNEST H. VOGEL, OF NEW YORK, N. Y.

ELECTRIC ELEVATOR.

SPECIFICATION forming part of Letters Patent No. 783,809, dated February 28, 1905.

Application filed April 11, 1904. Serial No. 202,563.

To all whom it may concern:

Be it known that I, ERNEST H. VOGEL, a citizen of the United States, residing in the city of New York, borough of Brooklyn, county of 5 Kings, and State of New York, have invented certain new and useful Improvements in Electric Elevators, of which the following is a specification sufficient to enable others skilled in the art to which the invention appertains to 10 make and use the same.

My invention relates to elevators, dumb-waiters, lifts, &c., in which a screw-drum actuated internally is employed as a means of raising and lowering the car or platform as 15 set forth in my concurrent application for patent, Serial No. 181,281, filed November 16, 1903.

My present improvements are designed to 20 simplify and cheapen the structure, to reduce frictional resistance, and to reduce the noise of running to the minimum.

The invention consists in the construction, combination, and arrangement of parts hereinafter described and claimed specifically.

25 In the accompanying drawings, Figure 1 is a horizontal section of a dumb-waiter and adjoining parts constructed according to my improvements. Fig. 2 is a horizontal section upon plane of line 2 2, Fig. 3. Fig. 3 is a vertical section upon plane of line 3 3, Fig. 1, certain parts being shown in elevation; Fig. 4, a sectional elevation upon plane of line 4 4, Fig. 1. Fig. 5 is a detail view illustrating the action of the upper and lower guide-rollers.

30 P represents the floor or platform of a lift, car, or dumb-waiter D, the drawings by way of illustration showing my improvements as applied to the latter structure.

To the under side of the platform P is rigidly secured a stud S, to the lower portion of which in turn is rigidly secured the cross-head C, preferably formed with a central annular spacing-shoulder c. On this spacing-shoulder c rests the hub a of the screw-drum 45 A, rotatable upon the stud S. A washer s' is preferably interposed between the hub a and the flanged base s of the stud S.

The screw-drum A is connected by spokes d or otherwise with the hub a, provided with 50 an annular tread or track d' for the bearing-

roller B, mounted axially at the rear of the platform P. This bearing-roller B distributes the weight to the drum A, preventing lateral strain upon the stud S and steadies the platform P.

The periphery of the drum A is formed with the spiral way or track p, as in my concurrent application hereinbefore referred to, said way or track p engaging with the supporting-wheels W W, axially mounted upon the upright U, as heretofore, but with this exception in the present case, that but a single vertical series of such supporting-wheels W is employed.

The car or platform P is sustained against 65 any tendency to lateral rotation on the screw-drum A by means of guide-rollers G G' engaging with stationary rails R in the elevator-shaft. These guide-rollers G G' also protect the stud S against undue lateral strain by 70 reason of uneven distribution of load on the platform.

The screw-drum A is rotated substantially as in my concurrent application before referred to, the operative parts, however, in 75 this case being suspended upon the bottom of the platform P by the single central stud S. Thus the brackets m m of the electric motor M are secured rigidly to the arms c^x c^x of the cross-head C, while the intermediate 80 gears i i' are mounted on the arms c' c' of said cross-head C. The intermediate gears i i' mesh into the annular rack a' on the interior of the drum on one side and with the driving-pinion m' on the armature-shaft 85 of the motor M on the other.

It will be seen that my present construction and arrangement of parts is simple, and therefore cheap, while experimental test has shown it to be effective and comparatively noiseless. 90

What I claim as my invention, and desire to secure by Letters Patent, is—

1. In an elevating device, the combination of a platform, a stud suspended from the under side thereof, a cross-head rigidly secured to said stud, an electric motor suspended upon said cross-head and formed with a driving-pinion upon its armature-shaft, a peripherally-threaded screw-drum suspended rotatably upon said stud and formed with an internal 95 100

annular rack, intermediate gearing mounted upon the said cross-head and meshing with the driving-pinion on the electric motor and with the said internal annular rack on the drum, and a series of vertically-arranged supporting-rollers for engaging the peripheral thread upon said drum, for the purpose described.

2. In an elevating device, the combination 10 of a platform, a stud suspended from the under side thereof, a cross-head rigidly secured to said stud, an electric motor suspended upon said cross-head and formed with a driving-pinion upon its armature-shaft, a peripherally-threaded screw - drum suspended rotatably upon said stud and formed with an external annular tread and with an internal annular rack, a bearing-roller axially supported on the platform and engaging the said external annular tread on the drum, intermediate gearing 15 mounted upon the said cross-head and meshing with the driving-pinion on the electric motor and with the said internal annular rack on the drum, and a series of vertically-arranged supporting-rollers for engaging the peripheral thread upon said drum for the purpose described.

3. In an elevating device, the combination 20 of a platform, a stud suspended from the under side thereof, a cross-head, rigidly secured to said stud, an electric motor suspended upon said cross-head and formed with a driving-pinion upon its armature-shaft, a peripherally-threaded screw - drum suspended rotatably upon said stud and formed with an internal annular rack, intermediate gearing 25 mounted upon the said cross-head and meshing with the driving-pinion on the electric motor and with the said internal annular rack on the drum, vertical guide-rollers supported axially upon the platform and engaging with vertical guide-rails in the shaft, said vertical guide-rails, and a series of vertically-arranged supporting-rollers for engaging the peripheral thread upon said drum for the purpose described.
